UNITED STATES PATENT OFFICE.

CARL E. SCHLOSSNAGEL, OF SWISSVALE, PENNSYLVANIA, ASSIGNOR TO WESTINGHOUSE UNION BATTERY COMPANY, OF SWISSVALE, PENNSYLVANIA, A CORPORATION OF PENNSYLVANIA.

STORAGE BATTERY.

Application filed January 29, 1927. Serial No. 164,577.

My invention relates to storage batteries of the lead-sulphuric acid type, and particularly to vent plugs for such batteries.

I will describe two forms of plugs embodying my invention, and will then point out the novel features thereof in claims.

In the accompanying drawing, Fig. 1 is a top plan view of one form of vent plug embodying my invention. Fig. 2 is a sectional view showing the plug inserted in the filling opening of a battery. Fig. 3 is a sectional view, similar to Fig. 2, of a modified form of vent plug also embodying my invention. Fig. 4 is a plan view of a detail of the plug shown in Figs. 1, 2 and 3.

Similar reference characters refer to similar parts in each of the four views.

Referring first to Fig. 2, the reference character 1 designates the cover of a storage battery. This cover has a filling opening surrounded by an upstanding flange 2 formed integrally therewith. On the inside of the flange 2 is an annular bead 3, provided with two diametrically spaced notches (not shown in the drawing) of the type employed in the usual bayonet fastening. The flange also has a bevelled portion 2^a near the top thereof. Associated with the filling opening is a vent plug designated generally by the reference character C. This plug is of tubular shape and is provided with an annular bead 4 having a plurality of wings 5 which serve as handles for the plug. The wall 7 of the plug C has two oppositely placed projecting lugs 6 which are arranged to co-operate with the notches in the bead 3, for the purpose of locking the plug in the opening. The wall 7 also has an annular groove 7^a for holding a gasket 8. When the plug C is inserted in the opening and forced downward so that the lugs 6 pass through the notches in bead 3, the projecting corner of gasket 8 engages the bevelled portion 2^a of the flange 2, and when the plug is rotated the lugs 6 engage the under side of the bead 3 and draw the plug C downward, deforming the gasket 8 and producing an acid-tight seal between the plug and the wall. The bevelled surface 2^a provides a single line of contact between the gasket 8 and the flange 2, so that the opening may be sealed with much less vertical pressure than would be the case if a flat sur-

face contact were provided between the gasket and the flange.

55

During the charging of the battery, gas is generated and this gas is usually allowed to escape through a small hole in the middle of the vent plug. This gas contains acid vapor which often condenses on top of the battery and causes corrosion of the metal parts. Ordinarily some of this vapor condenses at the bottom of the vent hole and forms a bubble which closes the hole. When this takes place the continued formation of gas in the battery produces a gas pressure which eventually becomes great enough to break the bubble, and in so doing, forces the acid outward in a fine spray over the top of the battery. In order to prevent this occurrence I provide the plug C with an inwardly extending frusto-conical projection having a substantially flat portion 12 and a bevelled side portion 12^a. Passing through the plug and terminating in the bevelled side portion 12^a, are a plurality (here shown as four) of spaced vent openings 13 which provide an escape for the gases generated in the battery. Any vapor which condenses on the inside of the plug will tend to run down the bevelled portion 12^a and to collect on the flat portion 12 away from the openings 13 so that gas may escape without spraying acid over the battery. It is also desirable that all the gases generated in the battery be allowed to escape, and in order to facilitate this escape and prevent gas from being trapped above the lower level of the vent plug where it cannot pass out through the vent openings in the plug, small openings 16 are made in the side wall 7 of the plug below the bottom of the gasket 8. With this arrangement the gas which collects in the space above the bottom of the plug between the side wall 7 and the flange 2 may pass through the openings 16 to the inside of the plug and then out through the openings 13, thus insuring that no gas pockets are formed in the battery.

In order to prevent the escape of acid from the openings 13 when the battery is subjected to severe vibration the usual baffle plate 9 of acid resistant material is mounted in the lower part of the plug C. An annular groove 11 is provided on the inside surface of the plug for holding the plate 9 in

105

place. When the plate is sprung into the groove, notches 10 provide openings through which the gases generated in the battery may escape, but these openings are of such size 5 that they prevent the escape of any appreciable amount of acid from the battery.

The vent plug shown in Fig. 3 is similar to that shown in Figs. 1 and 2, except that the arrangement of the gasket 8 and the 10 bevelled surface with which it co-operates is reversed, the bevelled surface being on the plug.

Referring now to Fig. 3, the flange 2 around the filling opening is provided with 15 a groove 14 in which the gasket 8 is mounted so that the inner surface of the gasket is substantially flush with the inside of the flange. The plug C¹ is similar to plug C except that it is provided with a bevelled 20 surface 15 below the bead 4, and this surface is arranged to engage the gasket 8 when the plug is inserted in the opening and locked in place. It will be seen that this arrangement provides a single line of contact between 25 the gasket and the plug, providing a simple and effective seal.

It will now be clear that a vent plug made according to my invention, not only prevents the spraying of acid over the top of 30 the battery and affords an escape for all gases in the battery, but also provides a seal which may be made effective by the exertion of a relatively small pressure on the plug, even in the case of large plugs such as are 35 used in large power batteries.

Although I have herein shown and described only two forms of vent plugs embodying my invention, it is understood that various changes and modifications may be 40 made therein within the scope of the appended claims without departing from the spirit and scope of my invention.

Having thus described my invention, what I claim is:

1. In combination, a storage battery cover 45 having an opening therein, an upstanding flange surrounding said opening and having its inner surface bevelled, a hollow plug associated with said opening and carrying a yieldable gasket, and means for forcing the 50 outside edge of said gasket against said bevelled surface when said plug is inserted in said opening.

2. In combination, a storage battery cover having an opening therein, a flange surrounding said opening and having a bevelled surface on the inside thereof, a hollow flanged plug arranged to fit in said opening, a sealing gasket associated with said plug, and means for securing said plug in 60 said opening, whereby a single line of contact between an outside edge of said gasket and said bevelled surface is secured.

3. In combination, a storage battery cover member having a circular opening therein, 65 a flange integral with said cover member and surrounding said opening, a hollow plug member for closing said opening, one of said members having a bevelled contact surface, a yieldable gasket carried by the other 70 of said members and one edge of which engages said bevelled surface, and means for securing said members together, whereby said gasket is forced against said bevelled surface to seal said opening.

4. In combination, a substantially flat storage battery cover having an opening therein, a flange surrounding said opening and having a bevelled inner surface, a hollow vent plug arranged to fit in said opening and having a plurality of spaced openings therethrough, a gasket associated with said plug, and means for forcing an outside edge of said gasket against said bevelled surface when the plug is inserted in said opening.

In testimony whereof I affix my signature.

CARL E. SCHLOSSNAGEL.
